UNITED STATES PATENT OFFICE.

WILLIAM C. ZIEGLER, OF ROCHESTER, NEW YORK, ASSIGNOR TO STECHER LITHOGRAPHIC COMPANY, OF ROCHESTER, NEW YORK, A CORPORATION OF NEW YORK.

FOLDING BOX.

1,144,746.

Specification of Letters Patent. Patented June 29, 1915.

Application filed February 5, 1915. Serial No. 6,354.

To all whom it may concern:

Be it known that I, WILLIAM C. ZIEGLER, of the city of Rochester, county of Monroe, and State of New York, have invented certain new and useful Improvements in Folding Boxes; and I do hereby declare the following to be a full, clear, and exact description of the same, reference being had to the accompanying drawings, forming a part of this specification, and to the reference-numerals marked thereon.

My invention has for its object to improve the construction of folding boxes with more particular reference to the type of box in which the body and cover are each folded from a single blank and held in such folded relation by means of coöperating parts on different portions of the blank.

The invention has for its further purpose to provide a construction which can be readily and quickly folded, and acts to retain the walls of the box securely in their proper assembled relation.

The invention is in the nature of an improvement on the construction disclosed in the patent of Goodnow, No. 695,205, granted March 11, 1902 and is intended to afford a more practicable and efficient arrangement for accomplishing the purposes of the patented structure.

To these and other ends the invention resides in certain improvements and combinations of parts all as will be hereinafter more fully described, the novel features being pointed out in the claim at the end of the specification.

In the drawings: Figure 1 is a plan view of a blank constructed according to my invention; Fig. 2 is a plan view with the side extensions on the side walls folded; Fig. 3 is a longitudinal sectional view showing the body portion and cover of a box constructed in accordance with the invention; Fig. 4 is a detail sectional view showing an end wall in folded relation to the side walls, and the extension on the end wall about to be finally positioned; Fig. 5 is a transverse sectional view showing the end extensions on the side walls, and the end wall, in folded relation, the extension on the end wall being in vertical position, and Fig. 6 is a perspective view of a corner of the box with the parts entirely folded.

Similar reference numerals throughout the several views indicate the same parts.

It will be understood that in the construction of a box of this character, the body portion and cover are both formed from similar blanks, the only difference being that one is slightly larger than the other in order to enable the body portion to fit within the cover. It will be unnecessary, therefore, to describe more than one of these parts and for convenience, I will explain the structure of the body portion which in the present embodiment comprises a bottom portion 1 having end walls 2, and side walls 3.

The side walls are provided with side extensions 4 which are adapted to be folded inwardly of the side walls in the manner shown in Fig. 2 and are preferably attached to the side walls by means of glue or in any other suitable manner. The side extensions 4 are provided with recesses 5 which are curved as shown and arranged intermediate the edges of the side extensions so that when the latter are folded inwardly of the side wall, the recesses will lie at points in spaced relation to the bottom of the box and preferably intermediate the top and bottom of the side walls, as shown clearly in Figs. 4 and 6. The side walls are also provided with end extensions 6 which are folded at right angles to the side walls when the box is assembled and lie adjacent to the end wall 2, as shown in Fig. 5.

The end walls 2 carry extensions 7 which are adapted to be folded inwardly thereof and over the end extensions 6 of the side walls in order to retain the latter in proper position as shown in Figs. 4 and 5. The extensions 7 carry locking tongues or extensions 8 which are curved to conform to the shape of the recesses 5 and are arranged intermediate the edges of the extensions 7. By this arrangement, when the extensions 7 are folded inwardly to their assembled positions shown in Fig. 6, the locking tongues 8 lie at points in spaced relation to the bottom of the box and preferably intermediate the top and bottom of the side walls, corresponding to the position of the recesses 5 on the side walls.

In assembling the parts, starting with a blank folded as shown in Fig. 2, the side walls are first bent upwardly, the end extensions 6 being turned inwardly to the position shown in Fig. 5. The end walls 2 are then bent upwardly as shown in Fig. 5 and the extensions 7 in turn bent downwardly

over the end extension 6 on the side walls in the manner shown in Fig. 4 until the tongues 8 spring into locking position in the recesses 5. The structure is easy to assemble owing to the fact that the locking tongue and coöperating recess are arranged above the bottom of the box rather than in juxtaposition to the bottom, as this makes it easier to reach the locking tongues and to bring the end walls and their extensions into final position. Furthermore, by making the locking tongues and recesses of curved formation and arranging them near the tops of the side walls, they have a closer engagement with each other and serve to hold the end wall extensions in tighter engagement with the end extensions on the side walls, all of which results in a more rigid, and consequently more efficient structure.

I claim as my invention:

A folding box comprising in combination a bottom portion and side walls having end extensions, an end wall having an extension foldable over the end extensions on the side walls and provided with locking tongues which are arranged intermediate the top and bottom of the box and are curved in opposite directions away from the end wall, the side walls having correspondingly curved recesses intermediate the top and bottom of the box and adapted to receive the aforesaid tongues whereby to maintain uniform engagement between the adjacent edges of the side wall and the end wall extension. 20 25 30

WILLIAM C. ZIEGLER.
